UNITED STATES PATENT OFFICE.

JOSEPH R. RICHER, OF CHICAGO, ILLINOIS.

PUMP.

Application filed September 23, 1920, Serial No. 412,297. Renewed December 22, 1925.

The invention relates to rotary pumps and its general object is the provision of a construction for a pump of this type which is of a practical character and which is efficient in operation.

More specifically stated, an important object of the invention is to provide a rotary pump in which a substantially continuous flow of liquid is capable of being maintained.

10 A further object of the invention is to provide a pump having a smooth and easy operation and one in which the noise of operation is reduced to a minimum.

15 A still further object of the invention is to provide a construction in which the return flow or leakage of liquid through the pump when idle is prevented.

The objects above set forth together with other advantages, are attained by the construction and arrangement shown in the accompanying drawings forming part hereof in which Figure 1 is a central longitudinal section through the pump casing, the operating means for the pump being shown in 25 elevation. Fig. 2 is a transverse sectional view through the pump taken substantially in the plane of line 2—2 of Fig. 1. Fig. 3 is a view similar to Fig. 2 but showing the operating means in a different position. 30 Fig. 4 is a fragmentary sectional view taken in the plane of line 4—4 of Fig. 3.

The pump comprises, in general, a casing 7 having an inlet 8 and an outlet 9. In one end of the casing there is provided a main 35 pump chamber or cylinder 10 in which a rotor 11 is mounted for operation, and in the opposite end of the casing there is provided an auxiliary chamber 12 having an oscillatory member 13 therein. Rigid with 40 the rotor 11 is a web or blade 14 which depends into the oscillatory member 13 and cooperates therewith to control the flow of liquid into and from the main and auxiliary chambers. The rotor 11 is operatively associated with a shaft 15 for movement thereby in a clockwise direction (Figs. 2 and 3). 45 In this operation, the periphery of the rotor contacts, with a rolling motion, the inner periphery of the main chamber or cylinder 10, and the oscillatory member 13 swings from side to side in the chamber 12, the arrangement being such that the rotor 11 and member 13 operate alternately to expel liquid from their respective chambers to the 50 outlet 9 and thus maintain a substantially uniform flow of liquid from the pump.

The casing 7 may be of any suitable construction. Herein it comprises a main portion 16 which is carried by a standard 17 mounted on a base 18. Rigid with the standard is a face plate 19 to which is secured by means of bolts 20, the main portion 16. On opposite sides of the casing, substantially intermediate the ends thereof, are provided the inlets 8 and 9 with which are connected an inlet pipe 21 and an outlet pipe 22 respectively. The chamber 10 is formed in the upper portion of the casing by the main portion 16 and the face plate 19, while the chamber 12 is similarly formed at the opposite end of the casing.

The rotor 11 is annular in form and of a diameter substantially greater than that of the shaft 15. The latter passes through said rotor and has bearings in the standard 17 and in the casing, a suitable stuffing box 15^a being provided around the shaft in the standard. A pin 23 extends transversely in the shaft 15 within the rotor 11, and has a portion projecting from one side of the shaft 80 and carrying at its free end a semi-cylindrical block or segment 24. Said pin is freely 85 slideable in its aperture in the shaft and a bow-spring 25, acting between the pin and the shaft, forces the pin outwardly and thus holds the segment in engagement with the inner periphery of the rotor 11. Herein the spring 25 is entered through a hole 25^a in the pin, and its free ends bear in notches 25^b in the shaft. By this construction, if any foreign substance should pass through the pump and enter between the rotor 11 and the inner peripheral wall of the cylinder 10, the spring 25 will yield to permit of the 90 passage of such foreign substance without injury to the operating mechanism. Moreover, in the event that the passage of the liquid through the outlet 9 should be cut off while the pump continues to operate, as by the accidental turning of a valve, the rotor 11 is capable of yielding to permit of the escape of the liquid in a reverse direction between the rotor and the cylinder.

The chamber 12 in the opposite end of the casing 7 is substantially triangular in form 105 so as to permit of the oscillatory movement of the member 13. This latter member is preferably constructed from a single piece of metal bent upon itself into substantially U-form to receive the blade 14 which is rigid 110 with the rotor 11 and projects from the periphery thereof. At the upper end of the

member 13 the opposite sides are rounded to provide a bearing member 26, and between the chambers 10 and 12 and the inlet and outlet passages 8 and 9, the casing is shaped 5 to provide a central elongated chamber 27 in which said bearing member 26 is seated. By reason of the peculiar construction of the member 13, the upper ends thereof constituting the bearing member 26 are normally 10 forced outwardly with a spring action into engagement with its seat. The upper surface of the portion 26 of the oscillating member is shaped as at 26^a so that when the rotor is in its lowermost position (Fig. 3) such 15 surface will form with the inner periphery of the cylinder 10 a continuous bearing surface with which the outer periphery of the rotor is adapted to engage. This construction is important in that it eliminates a difficulty 20 commonly experienced in pumps of this general character, to wit, the knocking or pounding of the rotor upon the edges of the opening into the cylindrical chamber, which leads from the inlet and to the outlet. 25 The blade 14 is adapted to fit snugly between the opposite side walls of the member 13, and the lower end portion 14^a constitutes a slide valve for controlling the flow of liquid into and from the chamber, and from 30 one side of the chamber to the other. The blade 14 may be secured to the rotor 11 in any suitable way. Herein it is entered through an elongated slot in the rotor and fastened thereto as by means of keys 28 35 (Figs. 3 and 4).

In passing from the inlet 8 to the chambers 10 and 12, and from said chambers to the outlet 9, the liquid passes through the oscillating member 13. To this end said 40 member 13 is provided in its upper portion 26, at opposite sides thereof, with a series of inlet ports 29 and outlet ports 30; its upper end with inlet and outlet ports 31 and 32 respectively; and its lower portion substantially centrally thereof with ports 33 and 34 located respectively at opposite sides of the member 13. As shown in Fig. 1, I have provided a plurality of each of said ports located in rows extending transversely of the 45 oscillating member so as to provide for relatively great capacity without weakening the structure. To permit of the flow of liquid from the ports 29 to the ports 33 and from the ports 34 to the ports 30, the blade 14 is recessed or grooved at its opposite sides as shown at 35 and 36. At its lower end, the oscillating member bears upon a transverse member 37 having a concave surface corresponding in shape to the lower end of the 50 oscillating member so as to prevent the passage of liquid around the bottom of the oscillating member. Said member 37 is yieldingly held in engagement with the lower end of the oscillating member, as by means of a bow-spring 38, so as to be permitted to yield 55

to allow the passage of foreign particles between it and the member 13, without injury to the pump.

In the operation of the pump, the shaft 15 is driven in a clockwise direction (Figs. 2 and 3). In Figs. 1 and 2 the rotor 11 is shown in the position which it occupies near the end of a cycle in which the liquid first drawn into the inlet side of the chamber 10 through the ports 29 and 31, in the upper end of the oscillating member, is then forced to the opposite side of the chamber in the succeeding rotation of the rotor, and finally is expelled through the ports 32 and 30. Thus, in Fig. 3, the rotor has drawn a quantity of liquid into the chamber 10, at the side adjacent the inlet 8, through the ports 29 and 31, and it will thus be apparent that in the continued movement of the rotor, the liquid which has thus previously been drawn into the chamber 10, will be forced upwardly around the rotor to the right hand side of the chamber, from whence it is expelled to the outlet 9 as the rotor completes its cycle of movement. 90

In such operation of the rotor 11, the blade 14 operating in the member 13 oscillates the latter in a general direction opposite to that of the rotor itself. Thus, as the rotor is commencing its upward stroke in the left hand side of the cylinder, the oscillating member is positioned at the right hand side of the chamber 12, and in the continued movement of the rotor 11 the oscillating member 13 swings to the opposite side of the chamber 12. In this movement, the valve member 14^a for the oscillating member moves with reference to the ports 33 and 34 so that the liquid is drawn first into the left hand side of the chamber 12 through the ports 29 and 33 and the groove 35, and then as the rotor continues its movement into the upper portion of the cylinder and thence downwardly the liquid is forced from the left hand side of the chamber 12 to the opposite side through the ports 33 and 34, such passage of the liquid being permitted by reason of the fact that the valve member 14 is positioned above said ports. Finally, as the rotor descends to the position shown in Fig. 3, the valve 14^a is moved downwardly below the port 34 so that communication between the chamber and the outlet is established through the ports 34, groove 36 and ports 30; and as the rotor 11 moves upwardly to the left (Fig. 3), the oscillating member is swung to the right. The liquid in the right hand portion of the chamber 12 is thus being expelled to the outlet, while the rotor is operating to force the liquid from the left hand side of the cylinder 10 to the other and to draw into the left side of the chamber a new supply. In the movement of the oscillating member toward the right to expel the liquid from the right hand por- 100 105 110 115 120 125 130

tion of the chamber 12, a quantity of liquid is drawn into the left hand portion of said chamber 12 for another cycle of operation.

The maximum displacement of liquid effected by the rotor 11 from the chamber 10 occurs during the movement of the rotor from a position at one side of the cylinder 10 upwardly and downwardly to the opposite side thereof or to the position shown in Fig. 2. During this movement of the rotor, the oscillating member 13 moves to the left in the chamber 12, forcing the liquid previously drawn into that portion of the chamber to the right hand side thereof. It will be apparent, therefore, that during the next portion of the movement of the rotor 11 from the position shown in Fig. 2 to the opposite side of the cylinder during which the minimum displacement of liquid takes place, the oscillating member moves to the right (Fig. 2) forcing the liquid therein to the outlet and thus compensating for the relatively smaller volume discharged from the cylinder 10 during this portion of its stroke. Consequently a substantially continuous and non-pulsating flow of the fluid from the pump is effected.

It will, of course, be understood that the rotor 11, oscillating member 13 and blade 14 extend entirely across the interior of the casing 7 so that any passage of liquid through the pump must occur through the ports and around the rotor in the manner especially provided. The grooves 35 and 36, it will be noted, terminate at their lower ends just above the valve member 14^a so that when the rotor is in its uppermost position, in which the passage of liquid through the ports 33 and 34 is permitted, the passage of liquid from the inlet 8 to the outlet 9 around the blade 14 is prevented. Thus in no position of the operating mechanism, when the latter is idle, is a return flow of the liquid from the outlet to the inlet possible.

By reason of the employment of the auxiliary chamber 12 and the oscillating member 13 in conjunction with the rotor 11, it will be apparent that the flow of liquid through the pump is maintained substantially continuous. When the rotor is acting to force liquid from the cylinder to the outlet, the oscillating member 13 is acting to force liquid from the left hand side of the chamber 12 to the other, and while the rotor is operating to force the liquid in the left hand side of the cylinder to the outlet side thereof, the member 13 is operating to expel the liquid from the right hand side of the chamber 12 to the outlet.

The bearing member 26 at the upper end of the oscillating member, it will be noted, constitutes a fulcrum upon which the member 13 is swung, thus eliminating any loose play between the blade 14 and the casing or between the oscillating member and the cas-

ing, and the upper concaved end of the oscillating member provides support for the rotor in its movement from one side of the chamber 10 to the other. Thus any tendency of the parts to knock and produce an objectionable amount of noise, and otherwise impair the efficiency of the pump is eliminated. Moreover, the special construction provided for the upper end of the oscillating member insures that the ball member 26 shall at all times have a bearing upon its seat.

The pump which I have provided is thus of a very practical character, and while I have herein described it with considerable particularity, it is to be understood that various changes in details of construction and arrangement may be made without departing from the spirit and scope of the invention as expressed in the appended claims.

I desire to point out, in particular, that in the operating means for the rotor 11, a spring for maintaining the segmental operating member 24 in contact with the rotor is not in all cases essential, since centrifugal force, especially in large pumps, may be depended upon to accomplish this purpose.

I claim as my invention:

1. A rotary pump comprising, in combination, a casing having an inlet and an outlet, a cylinder having a rotor eccentrically mounted therein, and an auxiliary chamber having an oscillating member therein operatively associated with the rotor so as to be driven thereby, said rotor and member being adapted to alternately expel liquid drawn from the inlet to the outlet.

2. A pump comprising, in combination, a casing having an inlet and an outlet, a cylindrical chamber, an auxiliary chamber, a rotor eccentrically mounted in the cylindrical chamber adapted to be driven so that its peripheral wall contacts the inner peripheral wall of the cylinder chamber, and an oscillatory member in said auxiliary chamber operatively associated with the rotor so as to be actuated thereby in the movements of the rotor, said member having a plurality of ports therein and a valve member operable to permit of the passage of liquid from the inlet to and from said chambers.

3. A rotary pump comprising, in combination, a casing having an inlet and an outlet, a cylindrical chamber, a rotor eccentrically mounted in said chamber, and valve means for controlling the flow of liquid from the inlet through said chamber to the outlet, said means comprising a member located between the inlet and the outlet and having ports establishing communication between the inlet and one side of the chamber and between the other side of the chamber and the outlet, and a member rigid with the rotor and having sliding engagement with said ported member whereby to pre-

vent the flow of liquid directly therethrough.

4. A rotary pump comprising, in combination, a casing having an inlet and an outlet, a cylindrical chamber and an auxiliary chamber, a rotor mounted in the cylindrical chamber eccentrically thereof, a member adapted to oscillate in said auxiliary chamber and having a portion seated between said inlet and said outlet so as to constitute a fulcrum therefor, said member having a plurality of ports therein establishing communication between the inlet and one side of each of said chambers and between the other side of each of said chambers with said outlet, and a part rigid with said rotor operatively associated with said oscillatory member whereby to control the flow of liquid by way of said ports from the inlet through said chambers to the outlet.

5. A pump comprising, in combination, a casing having an inlet and an outlet, a cylindrical chamber, an auxiliary chamber, a rotor eccentrically mounted within said cylindrical chamber so as to be capable of yielding radially inwardly from the peripheral wall of said cylindrical chamber, and an oscillatory member in said auxiliary chamber operable by said rotor, said rotor and oscillatory member being adapted to operate alternately to expel liquid from their respective chambers.

6. A pump comprising, in combination, a casing having a main chamber and an auxiliary chamber, a rotor in the main chamber and a reciprocatory member in the auxiliary chamber operable in the movements of the rotor to discharge from its chamber, during the minimum displacement stroke of the rotor, liquid drawn into said auxiliary chamber during the maximum displacement stroke of the rotor.

7. A pump comprising, in combination, a cylinder having a rotor therein adapted to discharge from the cylinder during one portion of its stroke a relatively greater volume of fluid than during the remaining portion of its stroke, and means associated with said cylinder and rotor adapted during the minimum displacement stroke of the rotor to effect the discharge of a compensating volume of fluid whereby to produce a substantially constant and non-pulsating flow of fluid from the pump.

8. A rotary pump comprising, in combination, a casing having an inlet and an outlet, a cylindrical chamber, an auxiliary chamber, a central chamber located between said inlet and outlet and between said cylindrical and auxiliary chambers, a rotor mounted eccentrically within the cylindrical chamber, an oscillatory member mounted in said auxiliary chamber, a blade depending into said oscillatory member, said oscillatory member having a portion seated in said

central chamber, and having ports controlled by said blade to permit of the passage of fluid from said inlet to said chambers and from the chambers to the outlet.

9. A rotary pump comprising, in combination, a casing having an inlet and an outlet, a main chamber, an auxiliary chamber, a central chamber located between said inlet and outlet and between said main and auxiliary chambers, a rotor mounted eccentrically within the main chamber, an oscillatory member mounted in said auxiliary chamber, a blade depending into said oscillatory member and seated in said central chamber said oscillatory member having ports controlled by said blade to permit of the passage of fluid from said inlet to said chambers and from the chambers to the outlet, said oscillatory member having its end adjacent the main chamber shaped to provide with the inner peripheral wall of said chamber a continuous bearing surface for supporting the rotor.

10. A pump comprising, in combination, a casing having an inlet and an outlet, a main or cylindrical chamber and an auxiliary chamber, a rotor eccentrically mounted within the main chamber, an oscillatory member operable in said auxiliary chamber, a hollow member seated between said inlet and said outlet and between said two chambers, and means for controlling the flow of liquid from the inlet to the chambers and from the chambers to the outlet, said hollow member having its surface adjoining the cylindrical chamber shaped to provide a support for the rotor in its movement from one side of the main chamber to the other.

11. A rotary pump comprising, in combination, a casing having an inlet and an outlet, a main chamber having a peripheral wall and a rotor eccentrically mounted therein, a central chamber between said inlet and outlet, and means for controlling the flow of liquid from the inlet to said chamber and from the chamber to the outlet including a member seated in said central chamber and providing a support for the rotor in the passage of the latter from one side of its chamber to the other.

12. A pump comprising, in combination, a casing having an inlet and an outlet, a main chamber having a rotor eccentrically mounted therein, an auxiliary chamber having an oscillatory member therein operatively associated with said rotor, means for controlling the flow of liquid from the inlet through said chambers to the outlet, and spring pressed means providing a yielding bearing for the free end of said oscillatory member.

13. A pump comprising, in combination, a casing having an inlet and an outlet, a chamber, a second chamber located between the inlet and the outlet and said first cham-

- ber, an oscillatory member operable in said first chamber and having a portion seated in said second chamber, said oscillatory member having valve-controlled ports therein 5 adapted in the movements of the oscillatory member to permit of the flow of liquid from the inlet first to one side of said chamber, thence to the opposite side of the chamber, and finally to the outlet. 10 14. A pump comprising, in combination, a casing having an inlet and an outlet, a chamber, a second chamber located between the inlet and the outlet and said first chamber, an oscillatory member operable in said first chamber and having a portion seated in said second chamber, said oscillatory member having valve-controlled ports therein adapted in the movements of the oscillatory member to permit of the flow of liquid from the inlet first to one side of said chamber, thence to the opposite side of the chamber and finally to the outlet, and means providing a yielding bearing for the free end of said oscillatory member. 15 15. A pump comprising, in combination, a casing having an inlet and an outlet, a chamber, a second chamber located between the inlet and the outlet and said first chamber, an oscillatory member operable in said first chamber and having a portion seated in said second chamber, said oscillatory member having valve-controlled ports therein adapted in the movements of the member to permit of the flow of liquid from the inlet first to one side of said chamber, thence to the opposite side of the chamber, and finally to the outlet, and a yielding member mounted in said first chamber and having its inner surface shaped to conform to the free end of the oscillatory member. 20 16. A pump comprising, in combination, a casing having an inlet and an outlet, a cylindrical chamber, an auxiliary chamber and a central chamber located between said inlet and outlet and the two first mentioned chambers, a rotor mounted eccentrically within said cylindrical chamber, an oscillatory member mounted in said auxiliary chamber and having a hollow portion seated in said central chamber, said rotor having a blade rigid therewith depending into said oscillating member through its hollow portion, said oscillating member having a plurality of ports therein through which liquid is permitted to flow from said inlet to said main and auxiliary chambers and from said two chambers to the outlet, the ports in the oscillatory member being adapted to be controlled by said blade whereby to permit the passage of fluid from one side of the auxiliary chamber to the other in the swinging movement of the oscillatory member. 25 17. A pump comprising, in combination, a casing having an inlet and an outlet, a cylindrical chamber, an auxiliary chamber and a central chamber located between said inlet and outlet and the two first mentioned chambers, a rotor mounted eccentrically within said cylindrical chamber, an oscillatory member mounted in said auxiliary chamber and having a hollow portion seated in said central chamber, said rotor having a blade rigid therewith depending into said oscillating member through its hollow portion, said oscillating member having a plurality of ports therein through which liquid is permitted to flow from said inlet to said main and auxiliary chambers and from said two chambers to the outlet, the ports in the oscillatory member being adapted to be controlled by said blade whereby to permit the passage of fluid from one side of the auxiliary chamber to the other in the swinging movement of the oscillatory member. 30 18. A rotary pump comprising, in combination, a casing having an inlet and an outlet, a chamber having an oscillatory member mounted therein and a second chamber, said oscillating member having a portion seated in said second chamber, a blade depending into said oscillatory member through said portion thereof, and means for swinging said blade, the hollow and depending portions of said oscillatory member each having a plurality of ports in its opposite sides, the ports in the depending portion being adapted to be directly controlled by said blade whereby to permit of the passage of liquid from one side of said first chamber to the other. 35 19. A rotary pump comprising, in combination, a casing having an inlet and an outlet, a main chamber, an oscillatory member providing a piston mounted in said main chamber, a second chamber, said oscillatory member having a hollow portion seated in said second chamber, a blade projecting into said piston through the hollow portion of the oscillatory member, and means for swinging said blade, said hollow portion and said piston each having a plurality of ports in its opposite sides, the ports in the piston being adapted to be directly controlled by said blade whereby to permit of the passage of liquid from one side of said first chamber to the other, and said blade having recesses in its opposite sides adapted to establish communication between the ports in said hollow portion and the ports in the piston to permit of the flow of pressure fluid into and from said first chamber. 40 20. A rotary pump comprising, in combination, a casing having an inlet and an outlet, a cylindrical chamber, an auxiliary chamber and a central chamber located between said inlet and outlet and the two first mentioned chambers, a rotor mounted eccentrically within said cylindrical chamber, an oscillatory member mounted in said auxiliary chamber and having a hollow portion seated in said central chamber, said rotor having a blade rigid therewith depending into said oscillating member through its hollow portion, said oscillating member having a plurality of ports therein through which liquid is permitted to flow from said inlet to said main and auxiliary chambers and from said two chambers to the outlet, the ports in the oscillatory member being adapted to be controlled by said blade whereby to permit the passage of fluid from one side of the auxiliary chamber to the other in the swinging movement of the oscillatory member. 45 50 55 60 65

- outlet, a chamber having an oscillatory member mounted therein, means for swinging said member including a blade depending into the member, said member having 5 a plurality of ports therein through which fluid is adapted to flow from the inlet into the chamber and from the chamber to the outlet, and said blade being adapted to control certain of said ports.
- 10 21. A rotary pump comprising, in combination, a casing having an inlet and an outlet, a substantially triangularly spaced chamber, a member located between the inlet and outlet and having a piston portion depending into said chamber, means for swinging said member, and valve controlled means for effecting the flow of liquid from the inlet to said chamber and from the chamber to said outlet in the operation of 15 said member.
- 20 22. A pump comprising, in combination, a casing having an inlet and an outlet, a substantially triangularly shaped chamber, a hollow member located between said inlet and outlet and having a piston portion depending into said chamber, said member
- having ports in its opposite sides located in the upper portion thereof and also in the lower portion thereof, a blade depending into said member and having a portion adapted to control the lower ports of said member, said blade having recesses in its opposite sides adapted to establish communication between the upper and lower ports of said member on the opposite sides thereof, and means for swinging said blade and thereby oscillating said member.
- 25 23. A pump comprising, in combination, a casing having an inlet and an outlet, two chambers disposed on opposite sides of said inlet and outlet, a piston in each of said chambers one of which has a rotary motion and the other an oscillatory motion, said pistons being operatively associated so that one of said members is driven by the other, and means for controlling the flow of liquid through the pump, said pistons being operable to expel liquid from the pump alternately from their respective chambers.
- 30 In testimony whereof, I have hereunto set 40 my hand.
